UNITED STATES PATENT OFFICE

139,376

DESIGN FOR A COMBINATION CLEANING AND POLISHING DEVICE

Marion H. Bissell, Chicago, Ill.

Application June 28, 1944, Serial No. 114,215

Term of patent 14 years

(Cl. D9—2)

To all whom it may concern:

Be it known that I, Marion H. Bissell, a citizen of the United States and a resident of Chicago, in the county of Cook and State of Illinois, have invented a new, original, and ornamental Design for a Combination Cleaning and Polishing Device, of which the following is a specification, reference being had to the accompanying drawing, forming a part thereof, and in which:

Fig. 1 is a side elevational view of a combination cleaning and polishing device showing my new design; and

Fig. 2 is an end view taken from the left of Fig. 1.

Both side elevational views of the device as shown in Fig. 1, are substantially the same, with the exception of the handle, which is related to the side elevational views in the manner shown in Fig. 2.

I claim:

The ornamental design for a combination cleaning and polishing device, as shown and described.

MARION H. BISSELL.
